UNITED STATES PATENT OFFICE.

WARREN A. BISHOP, OF LOWELL, MASSACHUSETTS.

SCREEN.

1,178,051.

Specification of Letters Patent.

Patented Apr. 4, 1916.

Original application filed October 31, 1914, Serial No. 869,625. Divided and this application filed June 26, 1915. Serial No. 36,450.

To all whom it may concern:

Be it known that I, WARREN A. BISHOP, a citizen of the United States, residing at Lowell, in the county of Middlesex and State of Massachusetts, have invented certain new and useful Improvements in Screens, of which the following is a specification, reference being had therein to the accompanying drawings.

10 The principal objects of my invention are to provide, first, a metallic frame for a screen, for doors, windows and the like, light in weight, rigid and durable in structure; second, means whereby the mesh of a screen 15 may with facility be secured to and removed from the frame, and stretched when secured to the frame; third, spring members adapted to be easily mounted, as upon a window frame, to engage suitable grooves in the 20 frame, control and guide the frame of the screen in its various positions and movements, and to subject the screen frame, that is the top and bottom bars of it, to tension rather than compression, thereby tending to 25 prevent a twisting of the frame, if of wood, out of shape; and other features that may appear hereinafter.

This application is a division of application for Letters Patent, for improvements 30 in screens, Serial No. 869,625, filed by me October 31, 1914, and those features of my invention not claimed herein, are described and claimed in said patent application.

In the drawings illustrating the principle of my invention, and the best mode now known to me of embodying the same in operative structure, Figure 1 shows my improved screen and guides arranged in a window casing, in front elevation; Fig. 2 is 40 a rear elevation of the screen; Fig. 3 shows a side elevation of the screen; while in the subsequent figures showing full sized details; Fig. 4 is a horizontal section of the screen on line 4—4, Figs. 1, 2 and 3; Fig. 5 is a vertical section on line 5—5 of Fig. 1; Fig. 6 is a vertical section of the corner portions of the frame, on line 6—6 of Fig. 4; Fig. 7 shows in perspective the construction at the corner portions of the screen; Figs. 8, 45 9 and 10 are respectively a plan, a longitudinal section, and a side elevation of screen guides; and Fig. 11 shows a guide engaging guide flanges of side piece in section.

50 A metallic frame 1, Figs. 1, 2 and 3, for a

screen comprises two parallel side guide pieces 2, parallel top and bottom pieces 3, 4, and screen-locking face-plates 5, 5'; all of which may be struck up out of thin suitable metal, by any well-known process. Each 60 side piece has a bottom 6, Figs. 6 and 11, two parallel sides 7, Figs. 4 and 7, of equal depth, with portions 8, bent inwardly at right angles, and forming lips lying in a plane parallel with that of the bottom, and 65 having their adjacent edges parallel, with a space between to form a longitudinal slot throughout the length of the side piece, and opening into the channel formed within the side piece.

The top and bottom pieces 3, 4, Fig. 5, are with the exception of their end portions 9, Figs. 6 and 7, L-shaped in cross section; each end portion 9 being an extension of one arm of the L and adapted to be bent 70 upon itself at right angles and toward the other arm of the L; and when assembled with the side pieces, capable of engaging and being secured to the outer end portion of the bottom of the channel in its respective side piece, as with small screws 10 and nuts 11. The structure so far described is 75 absolutely incapable of transverse bending.

To secure the mesh of the screen to the frame, a piece 12, see Figs. 4 and 5, is cut enough larger than the area of the inside of the frame to allow its edge portions to 80 overlay the faces of the side, top and bottom pieces of the frame. When the mesh is in proper position, the top and bottom locking plates 5', 5' and the side locking plates 5, 5, are placed over the edges of the mesh which by means of nuts 13, and screws 14, passing through the lock plates, the mesh and the four sides of the frame, become 85 rigidly secured to the frame in proper position. The interior edges of these lock plates have locking lips 15, Figs. 4 and 5, projecting inwardly against the mesh of the screen, but just beyond the edges of the 90 screen opening of the frame, so that, as the lock plates move into locking position on the frame, these locking lips by slightly bending, at the points of contact, the wires of the mesh out of a straight line, tend to 95 put them under tension and cause the mesh within the opening of the frame to lie perfectly flat, and remain in one plane. By arranging the top and bottom lock plates 5' so that they become rigidly fixed not only 100

110

to the top and bottom pieces 3, 4, of the frame, but also to the end portions of the trough-shaped side pieces 2 of the frame, the frame becomes absolutely rigid at its 5 four corners; and by reason of the shapes of its cross sections, the sides and the top and the bottom pieces of the frame cannot be bent transversely. In short, a frame constructed as above described is permanent in 10 shape; and the mesh of its screen may be easily mounted in, or removed from, the frame, and may be of a tension such as will cause it to lie flat.

Another feature of my invention resides 15 in a spring guide 16, Figs. 1, 8, 9, 10, and 11, adapted to be used with any frame provided it has the longitudinal grooves whose principle of operation and construction has just been described. It comprises 20 a spring plate having its two opposite end portions each provided with three downwardly and outwardly inclined fingers 17, 18, 19, that one in the middle 18 being designed to dig sufficiently into the wood, as 25 of a window casing 20, to hold the guides in operative position; while the other two fingers 17 and 19 have slightly upturned ends with beveled outside corners. Through the middle of the plate is a hole as for a 30 screw whereby when the plate is in operative position, a turning of the screw may tighten the tension of the spring plate more or less and correspondingly cause the middle fingers to settle into the material of the 35 frame upon which it is mounted. To prevent the screw from turning, the under side of its head has two prongs 21 which may slidingly engage two indentations 22 in the top of the spring guide 16. It will be noted 40 that the width of the middle fingers 18 is less than the width of the longitudinal slot in the side strips 2 of the frame, while the outside width of these fingers is less than the width of the groove but greater than 45 the width of the longitudinal slot; so that when one or more of these spring guides are arranged in alinement as upon the sides of a window casing 20, the inside surfaces of the lips 8 of the trough pass under the 50 outside spring fingers 17, 19 of the plates, the sides of which are in close proximity to the parallel sides of the groove, and hold the screws through the plates and the middle locking fingers out of contact with the 55 sides of the longitudinal slots in the side pieces of the frame. These spring members may be arranged in line, at suitable distances apart; metal threaded inserts 23 being permanently fixed in, say, window casing, 60 for the spring-controlling screws. Such a screw-hole member is not essential to my invention, but I find it extremely useful in that the frequent removals of the controlling screws cannot destroy the wood that 65 would otherwise be required to hold the

screw. In other words, the screw always has positive screw threads to engage.

To use my invention, two guide members opposite each other may be located as upon the window casing, and then two more, distant from the former less than the length of the side pieces of the frame. To mount the frame upon the guides, the top pair may be slightly inclined toward the user in a convenient plane so that the open ends of 70 the top of the side pieces of the frame, may be pushed under the adjacent ends of the spring fingers; and when in such position, the frame may, against the slight resistance offered by the lock fingers of the guides, be 75 swung into the normal plane of all the guides; and then forced downward into engagement with the lower pair of guides which at once contact the inside of the lock lips constituting the sides of the longitudinal slots in the side pieces of the frame. The frame is now in proper relation to the window frame, and the guides required above to permit the raising of the screen, 80 may, if not already in, be put into position; and when in position, the screen may be 85 lifted, as by finger grips 24 on the inside of the bottom piece 4 of the frame, and such additional guide members as may be needed placed between the guides first fixed to the 90 casing. To remove the screen frame, the reverse of the above-described operation may 95 take place; that is after a removal of only those guide members that prevent the screen frame from being swung out of the frame 100 of the window casing. In fine, by means of my invention I have done away with such objections as those arising from wooden frames that are flimsy; that are warped and 105 will not freely slide on their guides; or if not out of shape, that make use of wooden guide strips which in time become bent or broken and interfere with, or completely prevent raising or lowering the screen.

It is to be understood that the various 110 features of my invention may be varied without departing from the spirit thereof. For example, to use my spring finger guides, it is not necessary that the frame of the screen be of the particular construction shown, provided there are suitable longitudinal troughs or channels in the side pieces to engage the under sides of the spring fingers of the guide. Further, that feature 115 whereby the rigidity of the frame is obtained, is in no way dependent upon the particular shape of the groove slots for the spring guides. A wooden guide strip with suitable guide slots therefor, might, if 120 thought desirable, be used. Still further, the locking face-plates for giving tension 125 to the meshes of the screen do not require a metal frame. They can be used with an ordinary wooden frame having any kind of 130 guide slots and guides.

Desiring to protect all of the features of my invention in the broadest manner legally possible, what I claim is:

1. A window screen frame having in a side thereof, a guide channel partially closed longitudinally, a series of individual spring guides adapted to be arranged in alinement on the window frame and have their sides and under sides slidingly engage the narrow sides of the guide channel.

2. For a screen having guide slots partially closed longitudinally with a flange:— a spring guide comprising a metal spring plate having each of its two opposite end portions provided with three downwardly and outwardly inclined fingers; the middle finger being adapted to dig into a wooden window casing; and the two outside fingers having upturned ends, to slidingly engage the inside flanges of the screen; and means to secure the plate in operative position.

3. For a screen having guide slots partially closed longitudinally with a flange:—

a spring guide comprising a metal spring plate having each of its two opposite end portions provided with three downwardly and outwardly inclined fingers; the middle finger being adapted to dig into a wooden window casing; and the two outside fingers having upturned ends, to slidingly engage the inside flanges of the screen; a screw and a screw-reception member to secure the plate in operative position.

4. Two series of guide spring members having inwardly pressing spring fingers; and a screen frame having guide slots partially closed longitudinally, as by flanges; the inside portions of which are designed to be slidingly engaged by the spring fingers.

In testimony whereof I hereunto affix my signature in the presence of two witnesses.

WARREN A. BISHOP.
